CLAIM

The ornamental design for a robot control panel as shown and described.

DESCRIPTION

The patent or application file contains at least one drawing executed in color. Copies of this patent or patent application publication with color drawing(s) will be provided by the Office upon request and payment of the necessary fee.

1. Robot control panel

1. Reproduction 1 is a front view of a robot control panel in color

2. Reproduction 2 is a front view thereof in black and white. The robot control panel is a physical control panel for controlling a robot having a screwdriver or riveting pliers. Operating buttons of the robot control panel corresponding to the blurred square portions are disclaimed.
